Attorney

UNITED STATES PATENT OFFICE.

DAVID E. DE LAPE, OF LOS ANGELES, CALIFORNIA.

APPARATUS FOR TREATING HYDROCARBONS AND OTHER MATERIALS.

Application filed May 7, 1921. Serial No. 467,764.

This invention relates to an apparatus for treating materials, wherein the materials are subjected to heat and pressure for the purpose of causing physical or chemical changes in said material, and the invention is especially adapted to the treating of hydrocarbons to either crack or distil or both crack and distil the hydrocarbons.

An object of the invention is to subject material to heat while the material is under pressure, and to gradually relieve the pressure without diminishing the temperature.

More especially an object of the invention is to maximize the yields of hydrocarbons of the specific gravity desired.

In the art pertaining to the cracking of hydrocarbons, the heating of the hydrocarbons while under comparatively high pressures is well understood, the pressure making it possible to raise the temperature sufficiently to effect dissociation or "cracking", as it is commonly termed. In the known processes, the pressure is maintained at a predetermined degree during the cracking operation, and in some of the processes the pressure is removed before the cracked hydrocarbons are condensed, and in others of the processes, the pressure is maintained on the hydrocarbons while the condensing is effected. It is obvious that in these processes the vapor, as soon as evolved, is under pressure. An object of the present invention is to subject the hydrocarbons to sufficient heat and pressure to crack them while in a liquid state, and then to gradually diminish the pressure so that the lighter hydrocarbons will vaporize and will issue into the vapor chamber either under no artificial pressure or under a pressure that is less than the initial cracking pressure.

In its broader phases, the invention involves the passing of the material to be treated, whether liquid, semi-liquid or solid, through a molten bath or menstruum of metal or minerals or a combination of different metals or different minerals or a mixture of metals and minerals, thus to obtain maximum pressure on the material in the lower portion of the menstruum and a gradually reduced pressure as the material being treated rises to the surface, any vapors produced by the heating of the material freeing themselves from the menstruum and being either under atmospheric pressure or under whatever artificial pressure the refiner desires to impose thereon.

The invention involves the introduction into a molten bath of materials such as hydrocarbons alone or mixed with water, steam or any other desired medium so that, in the case of hydrocarbons, for example, said hydrocarbons will be cracked or distilled either without or in the presence of steam, as desired.

The accompanying drawings illustrate an apparatus built in accordance with the provisions of the invention and capable of performing the new process, but it is to be understood that the process is not limited to being performed in the apparatus shown and hereinafter described.

Figure 1 is a broken vertical mid-section of one form of the apparatus.

Figure 2 is a fragmental elevation, partly in section, of a modified form of the apparatus.

In the apparatus illustrated in Figure 1 there is provided a suitable chamber 1, in which is a molten bath or menstruum 2 of any suitable metal or mineral or combination of metals or minerals or a mixture of metals and minerals. The material employed for the molten bath will depend upon the temperature and pressure to which it is desired to subject the material being treated. As examples, the bath may be molten lead or copper or any other fusible material having a greater specific gravity than the material to be treated. In the lower portion of one of the side walls of the chamber 1 there is provided an opening 3 through which projects a supply pipe 4 for the introduction of the liquid or semi-liquid being treated. For example, hydrocarbons or a mixture of hydrocarbons and water or steam may be supplied through the pipe 4. The pipe 4 is provided with a valve 5 which may be operated to control the rate of flow of the liquid being treated. The pipe 4 may be connected with a suitable pump, not shown, to force the material, under pressure, into the chamber against the pressure of the menstruum. Of course, if deemed desirable, the oil, water, steam or other liquid or semi-liquid being treated could be introduced to the chamber through separate pipes.

Preferably the chamber 1 will be constructed in its interior with a tortuous passage composed of a series of coils or convolutions 6, the lowermost one of which connects with the inner end of the pipe 4. One advantage of the tortuous construction

of the passage is that it materially increases the actual distance through which the hydrocarbons must flow from the pipe 4 to the surface of the menstruum.

5 It may be desirable in some instances, though I do not limit the invention to their use, to employ pieces 7 of metal, minerals or metalloids. In the instance shown, these pieces of metal, mineral or metalloid are in
10 the form of spheres or balls, and they serve as an aid in breaking up the stream of hydrocarbons introduced through the pipe 4 so as to distribute the material being treated in a comparatively thin stream in the molten bath, thus to cause practically every particle
15 of the material to be surrounded by molten particles.

It is to be understood that the molten material constituting the bath is of higher specific gravity than the material which is to be treated so that said material will gradually ascend through the bath to the surface thereof. It is also understood that the pieces 7 are of higher melting point than the molten material of the bath so as to be distinct therefrom.

The menstruum may be melted and maintained in the molten condition by any suitable heating means, and I have illustrated a series of electrically-energized heating elements 8, each of which is inserted between two adjacent convolutions of the passage through which the menstruum flows. These heating elements are inserted in pockets 9 formed by the spaces between the coils and they are of sufficient size to produce the necessary heat for maintaining the bath in molten condition.

The uppermost convolution of the passage is provided in its top with an opening 10 covered by a screen 11 which permits the material being treated to pass therethrough but prevents the balls 7 from discharging from the passage. Above the screen 11 is a suitable space 12 into which the materials being treated can rise. Thus the balls will pile up beneath the screen and cannot all float to the surface of the molten material. This result is shown more or less diagrammatically in Fig. 1 as, in practice, the balls would actually be in contact with one another. This space 12 is surrounded on all sides by a wall 13 which is spaced from the wall of the chamber 1 to form a sump 14 into which materials that remain liquid can discharge from the space 12 by flowing over the upper edge of the wall 13. This liquid can be drawn from the sump 14 through a pipe 15 provided with a valve 16. Above the level of the wall 13 is formed a vapor chamber 17 which is mounted directly on the chamber 1.

The vapor chamber 17 may be of any suitable construction for receiving the vapors as they evolve. In this instance, I have

shown a vapor outlet 18 in the top of the chamber 17, a pipe 19 leading from said outlet to a suitable condenser or other apparatus, not shown, whereby recovery of the hydrocarbon vapors may be effected. Beneath the top of the chamber 17 is an inverted cone 20 which is spaced from the top to form a port 21 through which the vapors can pass to reach the outlet 18. The cone 20 is provided at its lower end with an opening 22 through which any condensates caught by the cone can flow into the liquid material occupying the space 12. 70 75

The vapors may be discharged from the chamber 17 through the pipe 19 as fast as they evolve, or, if desired, a valve 23 may be provided on the pipe 19 to make it possible to produce back pressure on the vapors. The chamber 17 is provided with a pressure gage 24 and with a safety valve 25.

Now referring more particularly to Figure 2 of the drawings, where not otherwise specifically mentioned the apparatus in Figure 2 employs the same elements as those described above, and those elements which can be seen in Figure 2 that are like those shown in Figure 1 will be indicated by the same reference characters with the addition of an exponent. In this form of the apparatus there is provided a burner 26 using liquid or gaseous fuels and the convolutions 6' of the passage are spaced from the walls of the chamber 1' so that the heat produced by the burner can flow around the convolutions, the space being indicated at 27. Instead of introducing the material through a pipe, as in Figure 1, there is provided a screw-conveyor 28 whereby solids and semi-solids that cannot be introduced through a pipe are forced into the lower-most convolutions 6'. 105

In practical operation, assuming, for example, that hydrocarbons are to be treated in the apparatus, the process is carried on as follows: The menstruum will be heated to a temperature sufficient to maintain it in molten condition and the hydrocarbons will be introduced under pressure into the lower portion of the menstruum, if liquid or semi-liquid through the pipe 4, or if solid through the conveyor 28. Thus oils may be introduced, tar, oil shale or the like. The menstruum column may be made of a height to produce the desired degree of pressure in the lower portion thereof so that the hydrocarbons thus introduced will be subjected to the desired degree of pressure. If a fractionating operation is all that is desired, the material of the menstruum and the temperature will be such as to cause vaporization of the lighter hydrocarbons at the surface of the menstruum, the heavier flowing into the sump 14 and being drawn off through the pipe 15. The lighter hydrocarbons in the form of vapor rise into the vapor cham- 130

ber and are drawn off through the pipe 19. The operation is the same if the hydrocarbons are to be cracked, excepting that a higher temperature is employed for the cracking operation.

It is clear that when the hydrocarbons are introduced into the lower portion of the menstruum the pressure imposed on said hydrocarbons is equal to the weight of the menstruum column, and that as the hydrocarbons rise the pressure gradually decreases until at the surface of the menstruum the pressure is atmospheric or only that imposed by creating back pressure of the vapors; that is to say, the vapors may be taken off under no appreciable pressure or they may be held under a pressure greater than atmospheric and less than the initial cracking pressure and condensed under such pressure. By having a series of heating elements arranged at different levels, the temperature of the menstruum may be more readily controlled at the different levels.

Though I have described the apparatus as employed more especially in the treating of hydrocarbons for the cracking or fractionating thereof, it is to be understood that the apparatus may be employed for treating sawdust, shavings and other woody material for the recovery of charcoal, pyroligneous acid, benzole, acetic acid and other substances and that dehydration and calcining are also possible in the apparatus. As examples of materials that may be calcined, among others are gypsum, ochers and the like.

It is to be understood that if it be desirable to heat a higher zone in the menstruum to a different temperature than a lower zone, different materials may be employed for the different zones, the material of the higher zone having a different melting point than that of the lower zone and being of a different specific gravity so as to remain in position above the level of the material of the lower zone. If the menstruum is homogeneous in character, the temperature thereof may be varied within the temperature scale lying between the melting and vaporization points of the menstruum, and if different materials are used for different zones in the menstruum the temperature of each material, and therefore each zone, may be varied within the temperature scale lying

between the melting and vaporization points of said material. Also, even though the 55 menstruum be homogeneous in character, zones of different temperatures may be created therein by heating the upper zones of the menstruum to a higher temperature than the lower zones. This is readily done because of the tendency of the cooler material 60 to gravitate to the lower zones.

I claim:

1. In an apparatus of the character described, the combination of a chamber having a tortuous passage, separate and independently operating heating means for different courses of said tortuous passage, a body of molten material in the tortuous passage, pieces of material in the molten 70 body of a higher melting point than said molten body, means to prevent some of the pieces of material from floating to the surface of the molten body and means to introduce material to be treated into the lower 75 course of the tortuous passage.

2. In an apparatus of the character described, the combination of a chamber, separate and selectively operable heating means at different levels in the chamber, a passage 80 extending upwardly from near the lower end of the chamber, a body of molten material in the passage, pieces of material in the molten body of a higher melting point than said molten body, means to prevent some of the pieces of material from floating to the surface of the molten body, a vapor chamber positioned above the first mentioned chamber, and means to introduce material to be treated into the lower portion of the molten 90 body.

3. An apparatus of the character described comprising a chamber, heating means for the chamber, a body of molten material in the chamber, pieces of material in the molten 95 body of a higher melting point than said molten body, a screen positioned below the surface of the molten body to prevent some of the pieces of material floating to the surface of the molten body, and means to introduce the material to be treated into the lower portion of the molten body.

Signed at Los Angeles, California, this 29th day of April, 1921.
